LAVATORY

Harry G. Coordes, Detroit, Mich., assignor to
 Briggs Manufacturing Company, Detroit, Mich.,
 a corporation of Michigan

Application November 24, 1944, Serial No. 564,963

1 Claim. (Cl. 4—166)

1

This invention relates to lavatories, wash basins, sinks, tubs or the like and particularly to an article of this kind formed from sheet metal.

An object of the present invention is to provide an article of the above kind formed from sheet metal and having an overflow channel or conduit of improved construction pressed or otherwise formed from sheet metal and attached to the back wall of the basin or sump to provide an overflow connection between the upper back wall drain opening and the drain pipe communicating with the bottom drain outlet of the basin or sump.

A further object of this invention is to provide a pressed metal article having a basin, bowl or sump provided with a channel shaped overflow conduit connecting the upper back wall drain opening with the drain pipe and formed with continuous laterally extending marginal flanging conforming to the contour of the back and bottom walls of the basin and secured thereto as by spot-welding the flanging to said walls.

Another object of the invention is to provide a pressed metal article of the kind mentioned above having a basin, bowl or sump provided with a separately formed overflow conduit formed of pressed metal which is porcelain enameled on the inside as well as the outside surfaces thereof.

Other objects of this invention will appear in the following description and appended claim, reference being had to the accompanying drawing forming a part of this specification, wherein like reference characters designate corresponding parts in the several views.

Fig. 1 is a plan view of a lavatory or wash basin embodying the present invention.

Fig. 2 is a section taken substantially through lines 2—2 of Fig. 1 looking in the direction of the arrows.

Fig. 3 is a section taken substantially through lines 3—3 of Fig. 2 looking in the direction of the arrows.

Before explaining in detail the present invention it is to be understood that the invention is not limited in its application to the details of construction and arrangement of parts illustrated in the accompanying drawing, since the invention is capable of other embodiments and of being practiced or carried out in various ways. Also it is to be understood that the phraseology or terminology employed herein is for the purpose of description and not of limitation.

Heretofore, in the production of lavatories of some cast iron types overflow conduits have been cast integrally with the back and bottom walls of the basin. This construction, although improving

2

the exterior appearance of the lavatory by eliminating the use of unsightly pipes, has not only had the disadvantage of increasing considerably the weight of the lavatory and the cost of manufacture due to difficult and expensive coring operations but also has been objectionable owing to the formation and accumulation of rust on the inside surfaces of the cast iron overflow which cannot be prevented since these surfaces are not capable of being porcelain enameled. Moreover, in the case of pressed metal lavatories, where it has been suggested to press or draw the overflow conduit integrally out of the metal of the basin, this has either proved impossible from a practical standpoint or has necessitated resort to a weld seam along the back and bottom of the basin requiring expensive finishing operations.

In accordance with the present invention an overflow conduit is first separately formed from sheet metal so as to provide a channel of adequate structural strength having continuous outturned flanging shaped longitudinally to fit the contour of the basin, and thereafter this member is applied to the back and bottom of the basin and spot-welded thereto at preferably closely spaced points entirely around the flanging thus producing a strong, rigid, light and exceedingly inexpensive construction. All surfaces of the overflow conduit including the portion thereof formed by the back and bottom of the basin are porcelain enameled thus preventing the formation of rust.

Referring to the drawing illustrating, by way of example, one embodiment of the present invention as applied to a lavatory or wash basin formed from a single blank or sheet of metal, such as sheet steel, the plumbing article, which may also be a sink, laundry tub or bathtub, comprises a drawn basin or bowl 10 having an upright back wall 11 merging on a curve 11a of relatively small radius into a bottom wall 12 which in turn merges into an upwardly sloping curved front wall 13. The basin or sump is also provided with upright side walls 10a which merge seamlessly into the back and front walls. The front and side walls 40 of the basin terminate at their upper edges around the three sides of the basin in a laterally extending ledge 14 of suitable width to support articles and this continuous ledge terminates in a depending apron 15 also extending continuously around 45 the basin. The lower edge of the apron 15 terminates along the lower edge thereof in a continuous inturned flange 16.

The ledge 14 around the front and sides of the basin merges into a rearwardly extending horizontal ledge 17 extending the full width of the

basin rearwardly of the upright back wall 11 thereof and this back ledge terminates in an upwardly extending splashback or panel 18 formed with a top horizontally extending ledge 19 of suitable depth which extends the full width of the basin. This ledge 19 is flanged along its rear edge to provide a wall flange 20. The depending apron 15 extends continuously around the front and sides of the lavatory and terminates at the back in line with the wall flange 20, as shown in Fig. 2.

The back wall 11 near its upper end is pierced to provide a number of overflow drain openings 21, three being shown by way of example, and each of these openings is formed with a continuous outwardly flanged edge 21a. The bottom 12 of the basin is embossed at 12a and the bottom of this embossment is pierced to provide a drain opening 12b. The overflow openings 21 and the bottom drain opening 12b are connected by means of an overflow conduit 22 which is pressed or otherwise formed from a single blank or strip of sheet metal. This conduit is formed into a channel in cross-section as shown in Fig. 3, so as to have adequate structural strength and rigidity and is shaped longitudinally so as to conform generally to the contour of the angularly related back and bottom walls 11 and 12. The channel or conduit 22, therefore, has a vertical portion extending substantially parallel to the back wall 11, a curved portion 22a formed on a greater radius than the radius of the curve 11a of the basin so as to position the bottom 22b of the channel or conduit at an increased distance from the bottom 12 of the basin. The bottom 22b of the channel or conduit extends somewhat beyond the drain opening 12b and thence is bent upwardly to provide an inclined portion 22c terminating in a flange portion 23 engaging and conforming to the shape of the adjacent bottom wall of the basin. The opposite end of the overflow channel or conduit is provided with a flange 24 engaging the back wall of the basin immediately above the outlet openings 21. Also, the sides of the channel or conduit 22 are formed with outturned flanges 25 which are shaped and bent to engage smoothly the back and bottom walls of the basin. The flanged portions 23, 24 and 25 form a continuous flanging extending entirely around the sides and ends of the channel or conduit 22 and are constructed so as to fit smoothly and uniformly against the adjacent surfaces of the back and bottom walls 22 of the basin, it being noted that the side flange portions 25 are bent intermediate their ends on a curve corresponding to the curvature 11a of the basin.

The foregoing construction provides a conduit in which the channel is relatively narrow along its vertical extension at the back of the basin and is relatively deep along its horizontal ex-

10 tension 22b beneath the bottom of the basin. The channel is rigidly and permanently secured to the basin in suitable manner, such as by spot-welding or seam-welding the flanging to the back and bottom walls of the basin entirely around the edges of the flanging. Spot-welding is in the present instance indicated at points 26 which are preferably close together continuously around the flanging to provide a tight joint between the juxtaposed surface of the flanging and basin.

15 The bottom wall of the overflow conduit portion 22b is pierced to provide an opening in line with the drain opening 12b, and a tubular fitting 27 extends downwardly through these openings. The upper flanged edge of the fitting lies within the embossment 12a and is drawn down tightly to provide a seal by means of a coupling nut 28 which connects the drain pipe 30 to the fitting 27, the latter being provided with suitable openings 29 through which the water overflowing into the conduit 22 passes into the fitting 27 and thence into the drain pipe 30. It will be seen that since the overflow conduit is formed as a structural channel having a flat bottom wall the coupling nut 28 may be drawn up tightly against the bottom of the channel to provide a seal through the medium of an interposed gasket while at the same time obviating any danger of distorting or collapsing the conduit at the locality of the union between the fitting 27 and the drain pipe 30.

20 It will be understood that the term lavatory, wash basin or the like used in the claim is to be constructed as comprehending plumbing articles of the kind hereinbefore mentioned including sinks, bathtubs, laundry tray units and laundry tubs in addition to the article shown in the drawing.

I claim:

25 40 A lavatory or wash basin comprising a pressed metal bowl including a bottom and an upright back wall having drain and overflow openings respectively, an overflow conduit connecting said openings and comprising a channel formed from a separate blank of metal and having a flat base and outwardly extending walls terminating in side and end flanging extending entirely around the channel, said conduit being bent to conform said flanging to the contour of said walls and said flanging being welded to said walls to provide a uniform tight contact of the juxtaposed surfaces of the flanging and walls, said base of the channel having a portion substantially parallel to the bottom of the bowl provided with an opening aligned with said drain opening and said base beyond the opening therein sloping upwardly and forwardly to engage the adjacent end flanging with the bottom of the bowl.

60 HARRY G. COORDES.
